CRAYON BOX OR PACKAGE

Earl L. Curtis, Sandusky, Ohio, assignor to The American Crayon Company, Sandusky, Ohio, a corporation of Ohio

Application November 22, 1934, Serial No. 754,236

1 Claim. (Cl. 206—44)

The present invention relates to a crayon box or package, and has for an object to provide a box for containing a number of crayons of different colors and which may be inspected without opening the box for ascertaining the various colors of the crayons of the package.

Another object of the invention is to provide a crayon box which may be of conventional or other type with the improved and peculiarly disposed sight openings through which may be observed independently the colors of the various crayons, the sight openings being symmetrically disposed through the wall of the box and in such relation to one another as to expose but one crayon through one opening or aperture.

A further object of the present invention is to provide a crayon box with sight apertures so arranged and proportioned as not only to admit of the inspection of the colors of the crayons within the box or package when closed, but to also support the crayons from the box when it is desired to remove the crayons for display, the sight openings or apertures being so disposed in the box as to accomplish this two-fold result and to properly and symmetrically support or display the crayons with their ends projecting through the openings in the box when set up for display.

The invention also aims to provide a box structure having combined display openings and crayon sockets in the wall of the box which are relatively arranged so as not to unduly weaken the wall or impair the strength of the box or package and also to increase rather than detract from the appearance of the box.

With the foregoing and other objects in view, the invention will be more fully described hereinafter, and will be more particularly pointed out in the claim appended hereto.

In the drawing, wherein like symbols refer to like or corresponding parts throughout the several views:—

Figure 1 is a top plan view of a crayon box or package constructed according to the present invention and with the crayons in the box with one crayon exposed through each of the sight openings.

Figure 2 is a top plan view of the box having the crayons removed therefrom and set up in the openings as sockets for supporting the crayons on display.

Figure 3 is a longitudinal section taken through the crayon box with the crayons therein, substantially on the line 3—3 of Figure 1, and

Figure 4 is a longitudinal section taken through the box on the line 4—4 of Figure 2, showing the

arrangement of the crayons in the openings for supporting the crayons in upright position.

Referring to the drawing the box or container has a body portion comprising top and bottom walls 10 and 11 and an end wall 12 which is relatively narrow so as to provide a box body which is relatively flat and wide. The edges of the box are closed by edge walls 13 and the mouth or open end of the box is preferably closed by a foldable tongue 14 adapted to be inserted through 10 an opening 15 in the bottom wall 11 of the box and with the marginal edge portion of the tongue lapped behind the marginal edge of the opening 15 in the bottom wall 10 as shown in Figure 3.

The flat wide body portion is proportioned to receive therein a row of crayons 16 which are of different colors, and the crayons are preferably disposed in parallel relation and with their blunt ends seated against the end wall 12 so that the crayons may be readily withdrawn through the open end of the box when the tongue or flap 14 is swung into open position.

In purchasing and handling crayons it is essential to determine the various colors thereof, particularly when it is desired to withdraw a crayon of a predetermined color from the box without removing all of the crayons therefrom. With this purpose in view the top wall 10 is provided with a plurality of sight openings 17.

In the particular embodiment of the invention herein shown, there is a sight opening 17 for each crayon 16 in the box, with the exception of the opposite end crayons of the row, and these opposite end crayons may be of certain colors found in most crayon assemblies such as brown and black, or other desired colors which may be otherwise indicated on the exterior of the box, if desired. Any suitable number and arrangement of the sight openings 17 and the crayons may be resorted to within the limits of the invention so as to expose more or less of the crayons as the size and character of the package may require. These sight openings 17 may be arranged as desired in a circular row, and may be disposed in a definite relation with respect to the row of crayons 16 and also with reference to the top wall 10 of the box so that the sight openings are spaced apart a suitable distance to provide sufficient material of the box body to prevent undue weakening of the top wall 10. It is also essential to symmetrically dispose the openings 17 so that the crayons may be readily inspected by a glance at the top of the box to determine the colors of the crayons 16 without repetition of the same color appearing through the sight openings 17.

For this reason the sight openings 17 are preferably arranged in a circular row and so spaced apart as to be disposed alternately or in staggered relation from edge to edge of the box with the openings offset lengthwise of the box so that there is a single sight opening 17 in register with but one portion of one crayon 16.

While the sight openings 17 may be of any desired size and shape, they may be as shown in the present instance circular in form to conform to the cylindrical shape of the crayons and may also be of suitable diameter for snugly receiving the ends of the crayons therein so that the sight openings 17 may form sockets for receiving the crayons 16, as shown in Figures 2 and 4, to hold the crayons in substantially upright position from the box when it is desired to display the crayons. In this instance the box body is used as a base or support adapted to lie flat upon a counter, a shelf or the like and the crayons may be inserted at their blunt ends in the openings 17 with the blunt ends projecting into the box body and resting upon the inner side of the opposite wall 11, as shown in Figure 4.

In order that the purchaser may determine the desired colors of the crayons, it is only necessary to inspect the sight openings 17 which show the different colors therethrough.

A very great advantage derived by the circular disposition of the cut-out holes or openings in the box is that the box may be used as a palette and the crayons may be inserted in the holes and maintained within easy access, and may be relatively disposed as to their colors to promote orderly color thinking and procedure.

After purchase, when it is desired to use a crayon of a particular color its location in the row may be quickly and easily determined by inspection of the crayons through the sight openings 17, when the selected crayon may be withdrawn

through the top of the box. The package also provides a neat and attractive appearance when set up for display purposes as the crayons may be tilted outwardly with respect to the center of the circular row of openings, as shown in Figures 2 and 4, so as to show the different colors and other characteristics of the crayons throughout substantially their entire lengths.

It is obvious that various changes and modifications may be made in the details of construction and design of the above specifically described embodiment of this invention without departing from the spirit thereof, such changes and modifications being restricted only by the scope of the following claim:—

What is claimed is:—

A crayon package comprising a box body having opposed flat walls, a row of crayons disposed in the box body with the crayons extending lengthwise thereof and the row of crayons extending from edge to edge in the box body, said box body having in one flat wall a plurality of symmetrically disposed combined sight and crayon supporting openings disposed in longitudinally and laterally off-set relation relative to the box body and with one opening in register each with one crayon, said openings conforming substantially to the size and configuration of the blunt ends of the crayons whereby the blunt ends of the crayons may be inserted in the openings to support the crayons in upstanding position, and said openings being arranged in said flat wall in a circle, said box body adapted to be placed flat against a support with the wall having the openings therein disposed uppermost for supporting the crayons in upwardly extending positions and with the blunt ends thereof resting against the inner face of the opposite flat wall of the box body.

EARL L. CURTIS.
